Primary Examiner — Anhdao Doan*Assistant Examiner* — Mary Shannon Malley(74) *Attorney, Agent, or Firm* — Walter A. Rodgers(57) **CLAIM**

The ornamental design for a microbiologically interactive growth platform, as shown and described.

DESCRIPTION

FIG. 1 is a perspective view of a microbiologically interactive growth platform showing my new design;

FIG. 2 is a bottom plan view thereof;

FIG. 3 is a top plan view thereof; and,

FIG. 4 is a side elevational view thereof.

The broken lines show portions of the microbiologically interactive growth platform that form no part of the claimed design.

1 Claim, 2 Drawing Sheets(56)
